UNITED STATES PATENT OFFICE.

WILLIAM B. BURGESS, OF BROOKLYN, NEW YORK.

DESIGN FOR WALL-PAPER.

SPECIFICATION forming part of Design No. 18,647, dated October 2, 1888.

Application filed August 18, 1888. Serial No. 283,146. Term of patent 7 years.

To all whom it may concern:

Be it known that I, WILLIAM B. BURGESS, of the city of Brooklyn, in the county of Kings and State of New York, have invented and produced a new and original Design for Wall-Paper, of which the following is a specification, reference being had to the accompanying drawing, forming part thereof.

My design consists of a surface ornamentation of small wavy lines, as shown by the letters *a a a a*, &c., on the drawing.

I claim—

The design for wall paper, as shown and described, the same consisting of a surface ornamentation of small wavy lines *a a a a*, &c.

WILLIAM B. BURGESS.
